UNITED STATES PATENT OFFICE.

GEORGE E. HULSE, OF NEWARK, NEW JERSEY, ASSIGNOR TO SAFETY CAR HEATING & LIGHTING COMPANY, A CORPORATION OF NEW JERSEY.

LAMP CONSTRUCTION.

1,309,630.

Specification of Letters Patent. Patented July 15, 1919.

Application filed March 28, 1916. Serial No. 87,155.

To all whom it may concern:

Be it known that I, GEORGE E. HULSE, a citizen of the United States, and a resident of Newark, in the county of Essex and State 5 of New Jersey, have invented an Improvement in Lamp Construction, of which the following is a specification.

This invention relates to lamp construction and with regard to the more specific 10 features thereof to supporting devices for the parts of electric lamps. One of the objects thereof is to provide practical and secure means for supporting certain parts of a lamp. Another object is to provide an 15 electric lamp construction which will be simple, compact and inexpensive and yet reliable in action and convenient in manipulation. Other objects will be in part obvious and in part pointed out hereinafter.

20 The invention accordingly consists in the features of construction, combinations of elements and arrangement of parts which will be exemplified in the structure herein-
25 after described and the scope of the application of which will be indicated in the following claims.

The accompanying drawing is a sectional elevation of one of various possible embodiments of this invention.

30 In this embodiment, the lamp, which includes not only the source of light but associated parts, is supported upon any suitable form of fixture indicated by the threaded nipple 1 by means of a collar 2. 35 This collar is provided with an outer annular groove 3 and about its surface is spun or otherwise formed the upper portion 4 of a shell or socket casing. This casing extends downwardly and thence outwardly to 40 form the shoulder 5 beneath which it is of general cylindrical form down to a portion 6 which has threads formed therein. As the casing is of sheet metal and these threads are formed by a suitable shaping thereof 45 rather than cutting its surfaces, there is provided a rounded thread upon both its inner and outer surfaces for purposes hereinafter described.

Beneath the portion 6 the casing flares 50 outwardly as at 7, thence curves inwardly at 8 and at its lower edge is outwardly flanged as at 9. The lower portion of this casing which is formed of spring brass, is slit at various points as indicated at 10 so as to 55 provide a plurality of depending resilient

fingers substantially of the shape shown in the drawing. These fingers are of such form that they normally tend to snap over the upper flaring lip 11 of the shade 12 of the lamp. Unless these fingers are restrained, 60 however, the lamp shade may be snapped into or out of position as the fingers readily yield to permit such action.

Threaded upon the outer surface of the threaded portion 6 is a clamping collar 14, 65 the lower portion of which flares outwardly at 15 and below is turned back upon itself at 16 to provide an upwardly converging or inner conical surface 17. The latter surface coacts with the outwardly flared portions 7 of the spring gripping fingers and as the member 14 is turned downwardly upon its thread, it securely clamps these fingers into interlocking relation with the shade. It may here be noted that the term 70 "shade" is used in a broad sense to denote any light-transmitting member used in connection with a source of light.

Fitted within the body portion of the casing 3 is a socket 18 which is preferably of the two-part type comprising an upper member 19 and a lower member 20 separable one from the other. These members are preferably formed of porcelain and interlock one with another as at 21. The upper member is provided on its lower surface with a contact plate 22 adapted to be engaged by the center contact of an ordinary electric bulb, and is also provided with a contact 23 adapted detachably to make electrical 80 connection with an internally threaded metallic sleeve 24 secured within the lower socket member 20. Suitable conductors 25 are led from contacts 22 and 23 respectively and pass upwardly through the nipple 1 to any desired source of current. Although the socket here shown is of the two-part type, certain of the features of this invention are independent of the type of socket employed and it is to be understood 85 that the term "socket" is broadly used to denote any device of this general nature.

The socket is held within the metallic shell or casing by means of a collar or bushing 26, which may be formed of fiber, and is threaded upon its outer side to fit and coact with the threads formed in the shell member at 6. This collar coacts with a stop shoulder 27 upon the socket member 20 and securely holds the socket in position. The 90 95 100 105 110

lamp bulb 28 may be of any well known form provided with the usual contacts adapted to coact with the contacts 22 and 24 respectively of the socket.

5 In the use of the device, the socket is assembled in a shell or casing 3 and is securely held in position by turning upwardly within the same the collar 26 which firmly engages the shoulder 27. The lamp bulb 28 may then be inserted and removed as desired. The shade is snapped within the spring fingers with the clamping collar withdrawn upwardly and the latter is then turned downwardly upon this same threaded 15 portion 6 of the shell and securely locks the spring fingers about the lip of the lamp shade. As the spring fingers are formed integral with the shell of the socket, the number of requisite parts is reduced and the 20 strength and reliability of construction increased as there is no tendency of these fingers, or the part with which they are connected, to work loose.

Furthermore, the formation of the thread 25 stamped within the walls of the socket in itself provides a threaded surface both internal and external to coact with separate parts as above described.

It will thus be seen that there is provided 30 a device of the most simple and inexpensive construction which is nevertheless essentially secure and practical in its action.

As various possible embodiments might be made of the above invention and as various 35 changes might be made in the embodiment above set forth, it is to be understood that all matter herein set forth or shown in the accompanying drawing is to be interpreted as illustrative and not in a limiting sense.

40 I claim as my invention:

1. In construction of the class described, in combination, a shade, a member adapted to make connection with and support said shade, a socket fitted within said member, a bushing threaded within said member and supporting said socket therein and a shade-locking device threaded on the outer surface of said member.

2. In construction of the class described, 50 in combination, a socket formed of two separable parts, a member fitted about both parts of said socket, means comprising a member threaded upon the outer surface of said first member adapted to support a shade, and a locking member threaded on the inner surface thereof adapted to extend below and to secure said socket.

3. In construction of the class described, 60 in combination, a socket formed of two separable parts, a member fitted about both parts of said socket, means comprising a member threaded upon the outer surface of said first member adapted to support a shade, and a locking member threaded on the inner surface thereof adapted to extend be-

low and to secure said socket, said first member being formed of sheet metal and bodily shaped to provide the threads with which said second and third members coact.

4. In construction of the class described, 70 in combination, a member having a resilient lower portion adapted to interlock with the lip of a shade, a socket formed of two separable parts both of which are incased by said member, said member being formed of sheet metal and having threads bodily formed therein, a bushing coacting with the inner surfaces of said threads to support said socket in position, and a member coacting with the outer surface of said threads 75 adapted to lock said resilient parts in interlocking position.

5. In construction of the class described, 80 in combination, a member having a resilient lower portion adapted to interlock with the 85 lip of a shade, a socket, said member being formed of sheet metal and having threads bodily formed therein, a bushing coacting with the inner surfaces of said threads to support said socket in position, and a member coacting with the outer surface of said threads 90 adapted to lock said resilient parts in interlocking position.

6. In construction of the class described, 95 in combination, a socket composed of two separable parts, a member formed of sheet metal for closely incasing and holding in position said two parts and provided with an outer thread and with resilient gripping fingers at its lower end, and a device 100 threaded upon the outer surface of said member and provided with an inclined surface adapted to engage said fingers and lock them into interlocking relation with a shade.

7. In construction of the class described, 105 in combination, a socket incasing member formed of sheet metal provided with an outer thread and with resilient gripping fingers at its lower end, a device threaded upon the outer surface of said member and provided with an inclined surface adapted to engage said fingers and lock them in interlocking relation with a shade, a socket composed of two relatively separable parts 110 fitted within said first member, and a threaded bushing threaded within said first member and extending below said socket and adapted to support it in position.

8. In construction of the class described, 120 in combination, a socket formed of a plurality of separable parts, a member fitted about two parts of said socket, means comprising a member threaded upon the outer surface of said first member adapted to support a shade, and a locking member threaded on the inner surface thereof adapted to secure said socket in position, said first member being bodily shaped to provide the threads with which said second and third members coact.

9. In construction of the class described, in combination, a member having spring fingers adapted to interlock with and hold in position a shade, a socket formed of a plurality of separable parts incased by said member, said member being formed of sheet metal and having threads bodily formed therein, a bushing coacting with said threads to support said socket in position, and a member coacting with said threads adapted to lock said resilient parts in interlocking position.
10. In construction of the class described,
- in combination, a member having a resilient lower portion adapted to interlock with the lip of a shade, a socket, said member having internal and external threads, a bushing coacting with the inner threads to support said socket in position, and a member coacting with the outer threads adapted to lock said resilient parts in interlocking position.

In testimony whereof, I have signed my name to this specification this sixteenth day of March, 1916.

GEORGE E. HULSE.
